UNITED STATES PATENT OFFICE.

JACOB CHRISTIAN HANSEN-ELLEHAMMER, OF COPENHAGEN, DENMARK.

CONTROLLING DEVICE FOR ENGINE DISTRIBUTING-VALVES.

1,318,664.

Specification of Letters Patent.

Patented Oct. 14, 1919.

Application filed May 13, 1919. Serial No. 286,910.

To all whom it may concern:

Be it known that I, JACOB CHRISTIAN HANSEN-ELLEHAMMER, a subject of the King of Denmark, residing at No. 147 Öresundsvæj, 5 Copenhagen, in the Kingdom of Denmark, have invented certain new and useful Improvements in Controlling Devices for Engine Distributing-Valves, of which the following is a specification.

10 This invention refers to a simple and easily operated device for controlling the in and outlet mechanisms, such as slides, valves, or the like of steam engines, compressed air engines, hydraulic engines, or similar engines, for the purpose of regulating the 15 speed of the engine or of reversing the engine.

Depending upon whether the cylinder or cylinders of the engine in question are stationary, or rotary, the said device consists of a rotating or stationary cam disk, against which the rods, or the like, which are connected with above mentioned members, press by means of rollers, or the like, and a circular, or approximately circular, disk which is disposed beside said cam disk against which circular disk said rollers, or the like, also press, and which is revolubly connected with said cam disk at an eccentric point or is 20 shiftable in its own plane in a direction transverse to the effective direction of the cam, and which, furthermore, is connected with or actuated by a controlling member, by means of which it can be caused to oscillate through a certain angle around said point or can be shifted a certain distance to one side or the other, and can be held fast in these extreme positions as well as in the central position and eventually in one or 25 30 35 40 45 50 55

more intermediate positions. When the circular disk is turned or shifted more or less to one side, said rollers, or the like, will not touch the corresponding side or half of the cam disk which, *e. g.*, corresponds to the forward movement of the engine, and the said members are consequently guided by the other side or half of the cam disk which other side or half, *e. g.*, corresponds to the reverse movement of the engine. When the circular disk is in its intermediate position, said rollers, or the like, since they now press against a surface, purely revolving around a center line will not transmit any motive power to said members, and the engine will consequently stop.

One form of construction of the aforesaid

control device is, by way of example, diagrammatically shown on the drawing, where the device is supposed to be used in connection with a rotating engine with three single-action cylinders.

Figures 1 to 4 represent an engine crank shaft in cross section, the control disks thereon and the adjusting mechanism therefor, the slide valves and connecting rods for the engine cylinders being indicated diagrammatically and the controlling devices being shown in different relative positions in these different figures.

Fig. 5 represents a side view of a portion of the engine crank shaft, an edge view of one of the control disks thereon, a section of the other disk thereon and an elevation of the contact end of one of the slide rods.

The same reference numbers indicate corresponding parts in the different figures.

The slides of the engine cylinders are indicated as rectangles 1. The other rectangles 2 indicate the inlet openings to the cylinders, not shown on the drawing. The straight lines 3 indicate the slide rods, which are actuated by springs not shown in a direction toward the center of the engine, and which, by means of rollers 4 press against the cam disk 5.

The latter is secured to the stationary crank-shaft 6 of the engine, and, on its lower half or third-part, has two guide-curves 7 and 8, one to the left and the other to the right of the stationary crank which is supposed to turn downward. On the upper part of the cam disk, the periphery of which may be circular, there is a turning-point 9 for the circular disk 10, which has a recess 11 for the crank shaft, and against whose periphery the rollers 4 also press. At a suitable point 12, the disk 10 is connected with the rod 13 of an eccentric 14, which by means of a lever 15, can be turned and secured in various positions 20, 21 on a segment 16.

An even transition for the rollers 4 from the disk 10, when the latter is swung out to the left or to the right, to the curve 7 or 8 on the cam disk 5 can be attained in various ways. For instance, when the rollers 4 are cylindrical as shown, the disk 10 can be given a somewhat greater diameter than the cam disk 5.

When the engine revolves in the direction indicated by the arrow 17, and the disk 10 assumes the shown extreme position to the

right, the piston in the lowest cylinder shown on the drawing will be approximately at the dead point, and the slide 1 will cover the inlet opening 2. Soon after this 5 the roller 4 will come from the disk 10 over on to the curve 7, and the slide will release the inlet opening. When the roller has passed the curve 7 and runs on the circular part of the cam disk 5, the inlet opening will 10 again be closed, but this closing does not need to be entire, for, as shown to the left on the drawing, there can still be retained a small inlet area 18. A little before the cylinder comes up into the upper position, the 15 roller 4 runs from the circular part of the cam disk 5 over on to the somewhat larger disk 10. Then the inlet opening is closed entirely; the other dead-center position is passed; and the outlet opening not shown 20 for exhaust steam is opened.

Now when the lever 15 is turned over to another point 21, *e. g.*, midway between the extreme point 20 and the central point 22 of the segment, the disk 10 will partially cover 25 the curve 7 as shown in Fig. 2, so that the latter will not act in its entirety, but only with a flatter and, eventually, shorter part. Consequently, the area of the steam inlet that is released each time will be decreased, 30 and the period of admission will eventually be shortened. Then the engine will run at, *e. g.*, half power. If the lever 15 is turned over to other points between 20 and 22, the power-capacity and speed will vary in a 35 corresponding manner. If the lever is placed opposite point 22 as shown in Fig. 3, the radial movement of the slides will entirely cease, and all the openings 2 will be closed, since the rollers 4 then only touch the larger 40 disk 10, so that not even the aforesaid little inlet area 18 is released. If the lever 15 is switched over to the other side of the segment, no matter whether to the extreme 45 point 23 or to a point between this and the central point 22, the curve 8 will be entirely or partially accessible for the rollers 4, so that, if the engine continues to rotate in the original direction, there will be given a counter-pressure in one or more cylinders, 50 and the engine is reversed. This result is thus attained simply by moving this single control lever. The controlling conditions during the new direction of run may be just like those described above, the mechanism 55 being constructed symmetrically with respect to the plane of the crank. This is, of course, not necessary, however.

When the engine is stopped, and when the lever 15 is then placed opposite some point 60 to the right or left of the central point 22, the engine will automatically start in the corresponding direction, either because one of the rollers 4 at once finds itself on the corresponding curve 7 or 8, or, when this is 65 not the case, simply because, to begin with,

the steam is let in through the little area 18, there always being a roller 4 on the circular part of the cam disk 5.

The shown details of the cam disk 5 and the disk 10 and of the controlling device are 70 immaterial to the invention and, in practice, they may be modified in many different ways, depending upon the kind of engine. The tracks on curves, on the parts 5 and 10, which actuate the connecting rods do not, of 75 course, need to be the peripheries of the disks.

I claim:—

1. A controlling device for the inlet and outlet members of an engine comprising a 80 cam disk having forward and reverse cam tracks on adjacent segmental sections thereof, a circular disk disposed side by side with said cam disk, one of said disks being eccentrically pivoted to the other and adapted 85 to oscillate thereon to open or close or partially open or close said forward or reverse cam tracks respectively, a crank shaft to which one of said disks is fixed, the other disk having a central slot through which 90 said shaft passes, valve-controlling slide rods provided with contact means engaging said disks, and means for shifting one of said disks to cause the circular disk to cover or partially cover one or the other of said cam 95 tracks.

2. A controlling device for the inlet and outlet members of an engine comprising a 100 cam disk having forward and reverse cam tracks on adjacent segmental sections thereof, a circular disk larger than said cam disk disposed side by side with said cam disk, one of said disks being eccentrically pivoted to the other and adapted to oscillate thereon to open, on close or partially open or close 105 said forward or reverse cam tracks respectively, a crank shaft to which one of said disks is fixed, the other disk having a central slot through which said shaft passes, valve-controlling slide rods provided with contact means engaging said disks, and means for shifting one of said disks to cause the circular disk to cover or partially cover one or the other of said cam tracks. 110

3. A controlling device for the inlet and outlet members of an engine comprising a 115 cam disk having forward and reverse cam tracks on adjacent segmental sections thereof, a circular disk disposed side by side with said cam disk, one of said disks being eccentrically pivoted to the other and adapted 120 to oscillate thereon to open or close or partially open or close said forward or reverse cam tracks respectively, a crank shaft to which one of said disks is fixed, the other disk having a central slot through which 125 said shaft passes, valve-controlling slide rods provided with contact means engaging said disks, and means for shifting one of said disks to cause the circular disk to cover or partially cover 130

tially cover one or the other of said cam tracks, and means for holding said shifting means in different positions.

4. A controlling device for the inlet and outlet members of an engine comprising a cam disk having forward and reverse cam tracks on adjacent segmental sections thereof, a circular disk disposed side by side with said cam disk, one of said disks being eccentrically pivoted to the other and adapted to oscillate thereon to open or close or partially open or close said forward or reverse cam tracks respectively, a crank shaft to which one of said disks is fixed, the other disk having a central slot through which said shaft passes, and means for swinging said circular disk in one direction to cover or partially cover the forward cam track, in the other direction to cover or partially cover the reverse cam track and to intermediate neutral position to cover both said cam tracks.
5. A controlling device for the inlet and outlet members of an engine comprising a

cam disk having forward and reverse cam tracks on adjacent segmental sections thereof, a circular disk disposed side by side with said cam disk, one of said disks being eccentrically pivoted to the other and adapted to oscillate thereon to open or close or partially open or close said forward or reverse cam tracks respectively, a crank shaft to which one of said disks is fixed, the other disk having a central slot through which said shaft passes, an eccentric, a rod connected therewith and with one of said disks, an adjustable lever for actuating said eccentric, and means for holding said lever in adjusted position.

In testimony that I claim the foregoing as my invention I have signed my name in presence of two subscribing witnesses.

JACOB CHRISTIAN HANSEN-ELLEHAMMER.
